Design Patent Application No. 29/205,081, Design Patent Application No. 29/205,091, Design Patent Application No. 29/205,149, filed concurrently with the present application, are related by subject matter.

FIG. 1 is a back view of a card assembly with vertical magnetic stripe showing a new design;

FIG. 2 is a front view of the embodiment of FIG. 1;

FIG. 3 is a side view of the embodiment of FIG. 1; and, FIG. 4 is a back view of a second embodiment of a card assembly with vertical magnetic stripe.

The broken line showing of card indicia, indicia box and punch out display hole are for illustrative purposes only and form no part of the claimed design.
